(57) **CLAIM**

We claim the ornamental design for a musical steel pan with drum sticks, as shown and described.

DESCRIPTION

FIG. 1 is a top perspective view of a musical steel pan with drum sticks, showing our new design,

FIG. 2 is a bottom perspective view thereof;

FIG. 3 is a top plan view thereof;

FIG. 4 is a bottom plan view thereof;

FIG. 5 is a left-side elevational view thereof, the right-side elevational view being a mirror image thereof;

FIG. 6 is a front elevational view thereof; and,

FIG. 7 is a rear elevational view thereof.

The broken lines in the drawings illustrate portions of the musical steel pan with drum sticks and form no part of the claimed design.
